L. STEPHENS

PLUG

Filed Nov. 28, 1921

UNITED STATES PATENT OFFICE.

LAWRENCE STEPHENS, OF MARIETTA, OHIO.

PLUG.

Application filed November 28, 1921. Serial No. 518,377.

To all whom it may concern:

Be it known that I, LAWRENCE STEPHENS, a citizen of the United States, and resident of Marietta, in the county of Washington 5 and State of Ohio, have invented certain new and useful Improvements in Plugs, of which the following is a specification.

This invention relates to packer plugs and is an improvement on the construction illustrated in my allowed application for patent, S. N. 403,475, filed August 14, 1920.

Briefly stated the invention forming the subject matter of this application resides in a packing plug preferably formed of a 15 single piece of wood or the like and having a plurality of segmental sections adapted to be moved longitudinally with relation to each other so as to increase the cross sectional area of the plug.

20 A further object is to provide a packing plug of the class described which is of highly simplified construction, simple to use and cheap to manufacture.

Other objects and advantages of the invention will be apparent during the course 25 of the following description.

In the accompanying drawing forming a part of this application and in which like numerals are employed to designate like 30 parts throughout the same,

Figure 1 is a perspective of the improved plug expanded.

Figure 2 is a group perspective of the improved plug.

35 Figure 3 is a horizontal sectional view taken on line 3—3 of Figure 1.

In the drawing wherein for the purpose of illustration is shown a preferred embodiment of the invention the numeral 5 generally designates the improved plug which is preferably formed from a single piece of wood or the like turned on a lathe or other suitable tool and having its end portions reduced to provide heads 6 and 7. Subsequent to turning the piece of wood on a lathe to provide the reduced end portions 6 and 7, the body of the plug is provided with a series of incisions which define segmental sections 8, 9, 10 and 11, the sections 8 and 9 being similar to each other while the sections 10 and 11 are similar to each other.

The sections 8 and 9 have plain surfaces 12 gradually decreasing in width toward the free end of the sections 8 and 9. More specifically each section 8 and 9 is provided

with a pair of plain surfaces 12 which decrease in width toward the free end of the sections whereby the cross sectional area of each section is decreased toward its free end. One surface 12 of the section 8 contacts with the opposed plain surface 12 of the section 9 so that when the sections are moved longitudinally with relation to each other the cross sectional area of the plug will be increased or decreased according to 60 the direction of movement of the sections.

Each of the sections 10 and 11 are similarly constructed and the section 11 is provided with flat contact surfaces 16 and 17, the contact surface 16 being gradually decreased in width toward one end of the section while the plain contact surface 17 gradually decreased in width toward the other end.

The section 10 which is constructed similarly to the section 11 is provided with a plain contact surface 18 which gradually decreases in width toward the upper end of the section and with another plain surface adapted to contact with the surface 17 and 70 which decreases in width toward the lower end of the section.

When cutting the stock into the sections as illustrated in Figure 2 the reduced head 6 is allowed to remain on the section 8 while 85 the reduced head 7 is allowed to remain on the section 9 and by reference to Figure 3 it will be seen that the diameter of the head 7 is less than the greatest diameter of the section 8 so that the head 6 will not interfere 90 with the insertion of the plug into the well to be plugged.

In assembling the sections of the plug, the terminal portion of the section 8 is arranged in contact with the terminal portion of the section 9 so that the cross sectional area of the plug is reduced to a minimum. The sections 10 and 11 are arranged in overlapping relation to each other and in overlapping relation with relation to the ends of the sections 8 and 9 whereby a more or less continuous body is provided. Before lowering the sections into a well the same may be lightly connected by means of small nails or the like and when the head 7 on the lower end of the 105 plug strikes the bottom a suitable tool may be engaged with the upper end or head 6 so as to move the sections longitudinally with relation to each other.

In operation the several sections may be 110

easily moved with relation to each other so as to effectively seal the well which may be either an oil, gas, water or other well.

Having thus described the invention, what is claimed is:—

1. A plug of the class described comprising a pair of segmental sections each having a pair of plain surfaces uniformly decreasing in width toward an end of the plug, and a second set of segmental sections cooperating with the first named sections in forming a plug of cylindrical formation, each of said second named sections being provided with two flat faces which decrease in width toward opposite ends, whereby longitudinal movement of one of the sections of the first and second named pairs of sections will enlarge the cross sectional area of the plug.
- 10 2. A plug of the class described comprising a pair of segmental sections each having a pair of plain surfaces uniformly decreasing in width toward an end of the plug, and a second set of segmental sections cooperating with the first named sections in forming a plug of cylindrical formation, each of said second named sections being provided with two flat faces which decrease in width toward opposite ends, whereby longitudinal movement of one of the sections of the first and second named pairs of sections will enlarge the cross sectional area of the plug.
- 15 20 25

ward opposite ends, whereby longitudinal movement of one of the sections of the first and second named pairs of sections will enlarge the cross sectional area of the plug, one of the first named pair of sections and one of the second named pair of sections being provided with a head.

3. A plug of the class described comprising a pair of segmental sections each having a pair of plain surfaces uniformly decreasing in width toward an end of the plug, and a second set of segmental sections cooperating with the first named sections in forming a plug of cylindrical formation, each of said second named sections being provided with two flat faces which decrease in width toward opposite ends, whereby longitudinal movement of one of the sections of the first and second named pairs of sections will enlarge the cross sectional area of the plug, one of said sections being provided with a head.

4. A packing plug for wells comprising a plurality of segmental sections having their opposed faces in contact, a pair of said sections being provided at their ends with heads.

LAWRENCE STEPHENS.
